UNITED STATES PATENT OFFICE.

CHARLES J. NAUEN, OF PATERSON, NEW JERSEY.

LOOM.

SPECIFICATION forming part of Letters Patent No. 695,622, dated March 18, 1902.

Application filed December 17, 1901. Serial No. 86,243. (No model.)

To all whom it may concern:

Be it known that I, CHARLES J. NAUEN, a subject of the Emperor of Germany, residing in Paterson, in the county of Passaic and State 5 of New Jersey, have invented certain new and useful Improvements in Looms; and I do hereby declare the following to be a full, clear, and exact description of the invention, such as will enable others skilled in the art to 10 to which it appertains to make and use the same, reference being had to the accompanying drawings, and to letters and figures of reference marked thereon, which form a part of this specification.

15 This invention relates to looms; and it consists in a loom having its parts constructed and arranged substantially as will be herein-after described and claimed and with the object, mainly, of placing on the shuttle or 20 other form of weft-carrier used the duty of being the initial factor in effecting its own actuation each time it is shot through the sheds of the warp.

By my improvement there need be but one 25 shaft—the ordinary crank-shaft—employed, and the loom may be otherwise simplified to great advantage without compromise with regard to the other necessary or desirable features of the ordinary loom as it has been 30 improved up to the present time and from some of which, in fact, even better results may be obtained.

My invention will be found fully illustrated in the accompanying drawings, in which—

35 Figure 1 is a vertical sectional view of the loom, the section being taken just forward of the batten. Fig. 2 is a view in side elevation of the loom, and Figs. 3 and 4 illustrate details.

In the frame *a* are arranged in the usual 40 manner the crank-shaft *b*, batten structure *c*, lay-swords *d*, carrying said batten structure and connected to the cranks *e* on the shaft *b* by pitmen *f*, picker-sticks *g*, warp-beam *h*, cloth-beam *i*, breast-beam *j*, and harness *k*.

45 One side of each shuttle-box *l* on the batten *c* consists of an elongated block *m*, which is arranged to turn on a pivot *n*, penetrating the block at the end thereof which is the nearer to the adjacent end of the batten and 50 being mounted in said batten. When the shuttle is driven across the lay or batten and enters the box, it tends to crowd or force the free or inner end of this block *m* outwardly.

In a bracket *p*, near each end of the batten,

is fulcrumed a bell-crank lever *q*, one end of 55 which extends upwardly parallel with the front face of the batten and opposite the inner end of the block *m*, while its other end extends rearwardly at a slight incline. When the block *m* is moved outwardly by the shuttle, it moves the bell-crank lever *q* and so raises its rearwardly-extending end. Normally—*i. e.*, when the block is not engaged by the shuttle, the shuttle being out of the box—gravity tends to hold the bell-crank lever in the position shown in Fig. 2, the rearwardly-extending arm of said lever being 60 longer than the other arm. 65

On each side of the loom is fulcrumed a substantially vertical lever *r*, which carries a 70 plate *s*, arranged back of the rear end of the adjacent bell-crank lever *q*. This plate is pivoted at *t* and is held against the stop *u* by a spring *v* on the lever for reasons herein-after pointed out. 75

In bearings *w*, adjacent each lever *r*, is fulcrumed another lever *x*, having its lower end formed as a hook *y* and having its other end drawn away from the lever *r* by a spring *z*, which connects it with the arm. The levers 80 *r* and *x* are connected by a stem or link *l*, which is pivoted to the lever *r* and penetrates the lever *x*, being threaded and provided with nuts *2*, whereby the connection between the two levers is adjustable. 85

3 designates another lever, which is pivoted in each side frame of the loom, extending substantially horizontal. Its rear end carries an antifriction-roller *4*, which bears against a 90 cam *5* on the shaft *b*. By means of a coupling *6* its front end is connected to a pitman *7*, which is in turn connected at its lower end to a short angle-lever *8*, which is fulcrumed on a pin *9*, traversing a loop *10*, formed at each end of a shaft *11*. The picker-stick, it should 95 be remarked, is fulcrumed on the pin *9*, while the lay-swords *d* have bearings on the shaft *11*, as usual. The picker-stick carries an angle-iron *12*, between which and the picker-stick a lug *13* on the angle-lever has 100 slight movement. Each picker-stick is connected with the loom-frame by means of a buffer-spring *14*.

15 is a spring connecting the two angle-levers *8* and tending to draw their upwardly-extending arms toward each other, as seen 105 best in Figs. 1 and 2.

It should be remarked that each lever *3* car-

ries a pin 16, which is adapted to be engaged by the hook portion *y* of the lever *x*, which latter thus holds the forward end of the lever 3 elevated, so that said lever, the pitman 7, and 5 the angle-lever 8 pull against the spring 15.

The loom operates as follows: The shaft *d* rotates continuously, imparting the usual reciprocating motion to the batten through the pitmen *f*. The shuttle being in one of the 10 boxes, the block *m* is pushed by said shuttle outwardly, so that it engages the bell-crank lever *q* and raises the rearwardly-extending portion thereof. This is while the batten is forward. The batten now moves back, where- 15 upon the rearwardly-extending portion of the bell-crank lever *q* engages the plate *s*, which by stop *u* presses the lever *r* back. This action effects the actuation of the lever *x*, so that the hook *y* thereof disengages the pin 16 20 and permits the forward end of lever 3 under the pull of spring 15 to drop, the shaft *b* having meantime turned so that the low part of the cam 5 is opposite the roller 4. The lever being thus released permits the angle-lever to 25 be actuated by the spring 15, so that said angle-lever by means of its lug 13 strikes the picker-stick, which in turn drives the shuttle across the batten. The operation is then re- 30 peated on the other side of the loom. The shuttle being shot across the batten, the levers *r* and *x* are released, so that the spring *z* may draw them to their original position—*i. e.*, where when the cam 5 depresses the rear 35 end of the lever 3, so as to reset the picker-stick, the pin 16 on the forward end of said lever will engage the hook *y* of the lever. It will be understood that where there is no shuttle in the box—*i. e.*, in every alternate pick of the loom—the rear end of the bell-crank lever *q* will be permitted to drop sufficiently, so 40 as to clear the plate *s*, with the result that the lever *r* and parts which it controls will remain unactuated.

It has been hereinbefore remarked that the 45 plate *s* is yieldingly arranged on the lever *r*. It should be also remarked that the rear end of the bell-crank lever *q* is formed with a rise or hook 17. When the rear end of the lever *q* is moved backward, it first pushes against 50 the plate and then slips past under the lower edge thereof. The rise or hook 17 of said lever makes the lever dip lower in clearing the plate than it otherwise would, and so the end of the lever which engages the block *m* presses 55 momentarily harder against the block, thus making the latter serve as a shuttle-binder. It should be remarked that at this instant the shuttle enters the box. The object, therefore, of mounting the plate yieldingly is to permit 60 it to give way to the rise or hook 17 as the lever *q* again advances.

By virtue of the adjustment afforded by the connection between the levers *r* and *x* the lever *x* may be set so as to release the shuttle- 65 actuating mechanism at exactly the proper time after the shuttle has entered the box.

Having thus fully described my invention, what I claim as new, and desire to secure by Letters Patent, is—

1. In a loom, the combination of the bat- 70 ten, a weft-carrier arranged on said batten, and a spring-controlled weft-carrier-actuating means, said actuating means being controlled by said weft-carrier, substantially as de- 75 scribed.

2. In a loom, the combination of the bat- 80 ten, a weft-carrier arranged on said batten, a spring-controlled weft-carrier-actuating means, mechanism for maintaining said actuating means set against the tension of its spring, and means, controlled by said weft-carrier, for actuating said mechanism to release the actuating means, substantially as de- 85 scribed.

3. In a loom, the combination of the bat- 90 ten, a shuttle arranged on said batten, a spring-controlled shuttle-actuating means, mechanism for maintaining said actuating means set against the tension of its spring, and means, comprising a part movable into the path of 95 the shuttle on the batten and adapted to be moved by said shuttle, for actuating said mechanism to release the actuating means, substantially as described.

4. In a loom, the combination of the bat- 95 ten, a shuttle arranged on said batten, a spring-controlled shuttle-actuating means, mechanism for maintaining said actuating means set against the tension of its spring, means for moving said actuating means into engagement with said mechanism, and means, controlled by said shuttle, for actuating said mechanism to release the actuating means, substantially as described.

5. In a loom, the combination of the bat- 105 ten, a shuttle arranged on said batten, a spring-controlled shuttle-actuating means, a system of levers, means for moving said shuttle-actuating means into engagement with said levers to maintain said means set against the 110 tension of its spring, and means, controlled by said shuttle, for actuating said system of levers to release said shuttle-actuating means, substantially as described.

6. In a loom, the combination of the bat- 115 ten, a shuttle arranged on said batten, a spring-controlled shuttle-actuating means, a system of levers, a rotating cam-shaft, said shuttle-actuating means being adapted to be moved by said cam-shaft into engagement with said 120 levers to maintain said means set against the tension of its spring, and means, controlled by said shuttle, for actuating said system of levers to release said shuttle-actuating means, substantially as described.

In testimony that I claim the foregoing I have hereunto set my hand this 9th day of December, 1901.

CHARLES J. NAUEN.
